WILLIAM O. WARNER, OF KENMORE, NEW YORK, ASSIGNOR TO CURTISS AEROPLANE
& MOTOR CO. INC., A CORPORATION OF NEW YORK

CAM-SHAFT DRIVING MECHANISM FOR INTERNAL-COMBUSTION ENGINES

Application filed April 10, 1925. Serial No. 22,239.

My invention relates to internal combustion engines and is more particularly concerned with the cam shaft driving mechanism thereof.

Ordinarily the cam shaft driving mechanism, and hence the cam shaft, cams and valve gear of an internal combustion engine, are subjected to the torsional vibrational stresses of the engine crank shaft, which, in an aero-
10 nautical engine, are oftentimes exceedingly heavy, due to the fact that the propeller, driven by the engine, is directly mounted on an extension of the crank shaft itself. Such an objectionable condition is partially over-
15 come by the provision of a propeller shaft, separate from the crank shaft, which propeller shaft, tho directly geared to the crank shaft, is nevertheless yieldingly geared or coupled thereto by means of a spring cou-
20 pling. Where a geared propeller shaft is employed, invariably the gear for driving it is in no way related to nor does it form, in a single instance, a part of the cam shaft driving mechanism. Usually the propeller shaft
25 gearing is mounted at the propeller end of the motor and the cam shaft driving mechanism is mounted at the anti-propeller end, such an arrangement necessitating a duplication or multiplicity of gears and shafts, all
30 of which gears and shafts tend to increase materially the complexity, the weight per horsepower, and the production cost of the engine. In an aeronautical motor, anything tending to increase the weight per horsepow-
35 er, the complexity, the size and the cost thereof, without improved performance, should by all means be eschewed.

By the present invention, instead of providing, at opposite ends of the engine, mechanism, for driving a propeller shaft and separate mechanism for driving the cam shaft, it is proposed to combine the two, i. e., drive the cam shaft and its associated valve gear thru shafts and gearing directly geared to a large
45 reduction gear forming an actual part of the propeller shaft driving mechanism. Preferably such large reduction gear has associated with it a spring coupling of more or less conventional design, which coupling, in view of
50 its relation to the cam shaft driving mecha-

nism, relieves the latter, and also the crank shaft, of all torsional vibrational stress. Moreover, in combining the driving mechanisms, the weight per horsepower and the production cost of the engine are very appre-
55 ciably reduced, a lesser number of gears and shafts are required to be used, and a more compact engine structure is the result. Obviously such important considerations are greatly to be desired in an aeronautical en-
60 gine as distinguished from an engine de-
signed for a different use.

In the drawings, wherein like reference characters denote like or corresponding parts,

Fig. 1 is a semi-diagrammatic end elevation, partly in section, of an aeronautical engine, showing the relative arrangement of the shafts and gearing constituting the cam shaft driving mechanism and the propeller shaft driving mechanism which forms a part 70 thereof;

Fig. 2 is a similar view, in side elevation, of the mechanism illustrated in Fig. 1;

Fig. 3 is a face view of the large reduction gear with a portion of the outer gear covering 75 removed, showing in part the spring coupling which is built into and made an actual part of the said reduction gear;

Fig. 4 is a transverse sectional view of the reduction gear of Fig. 3, and

Figs. 5 and 6 are views similar to Fig. 1 illustrating slight modifications of the cam shaft driving mechanism.

The invention, while illustrated in connection with the so-called V and W type motors, 85 can be equally as well used in connection with motors of the "straight line" type. If used in connection with a V type motor, parts of the cam shaft driving mechanism are duplicated. If used in connection with a W type 90 motor, such parts instead of being duplicated, are triplicated. Whether or not duplication or triplication is required depends wholly upon whether or not there are two or more cylinder banks. In Fig. 1 of the drawings a V type motor 95 is shown. In Figs. 5 and 6 W type motors are shown. Such motors, regardless of type, include a crank case 10, a crank shaft 11, a propeller shaft 12, and over-head cam shafts 13, two for each cylinder bank. (One, instead of 100

two cam shafts per cylinder bank, may be used if desired.) From the crank shaft 11 power is conveyed to the propeller shaft 12 by suitable gearing. Preferably such gearing 5 includes a driving gear 14 and a large reduction or driven gear 15, the latter, or reduction gear (see Figs. 3 and 4), having associated with it a more or less conventional spring coupling 16. Such coupling provides a yielding 10 driving connection between the crank shaft and the propeller shaft to adequately absorb all torsional vibrational stresses occurring in operation.

The reduction gear 15 and its associated 15 spring coupling 16 have been heretofore employed. Prior structures, however, call for an independent and wholly disassociated cam shaft driving mechanism. Usually the cam shaft driving mechanism is mounted at the 20 end of the engine opposite to the reduction gear, i. e., the anti-propeller end. In the present invention a novel combination is effected: Instead of providing an independent cam shaft drive, the cam shaft drive 25 is directly associated with the large reduction gear. The reduction gear may be therefore said to constitute an integral part of the cam shaft driving mechanism.

From the large reduction gear 15 motion is 30 transmitted to a spur gear 17 mounted on a stub shaft 18 having an axis of rotation directly above and parallel with the axis of rotation of the propeller shaft. Said spur gear 17 is at all times in mesh with the large 35 reduction gear. The shaft 18 is further provided with a bevel gear 19. In the V type motor of Fig. 1 and in the W type motor of Fig. 5, all of the several cam shafts are 40 indirectly driven from said bevel gear, and from said bevel gear 19, shafts 20 radiate, one shaft 20 being extended off from the bevel gear in the direction of each cylinder bank. Each shaft 20 carries at its opposite ends 45 bevel pinions 21 and 22, the former being in mesh with the bevel gear 19 and the latter being in mesh with a bevel gear 23 mounted on a stub shaft 24, journaled in bearings (not shown) provided at the outer end of each cylinder bank. In addition to the bevel gear 50 13, each shaft 24 is provided with a spur gear 25, said gear being in mesh with duplicate spur gears 26 mounted one each on each of the respective cam shafts 13. Where but a single cam shaft is provided for each bank this duplication of gears 26 may be dispensed with.

In Fig. 6 of the drawings a slightly modified arrangement of shafts and gearing is shown. In said figure, instead of driving 60 the respective sets of cam shafts 13 from the bevel gear 19, the cam shafts of the two outer cylinder banks are driven from the bevel gear 23 provided at the outer end of the center cylinder bank. In other words, the shafts 20 65 radiate from the bevel gear 23 of the center

cylinder bank instead of from the bevel gear 19 mounted on the stub shaft 18.

From the above, it will be observed that the cam shaft drive mechanism enters into and forms an actual part of the propeller shaft driving mechanism, such dual use of the latter mechanism permitting a great saving of weight. It is the old practice to provide suitable cam shaft driving mechanism at the anti-propeller end of the motor and the propeller shaft driving mechanism at the propeller end, and while such an arrangement is instrumental in relieving the cam shafts and the valve gear associated therewith from torsional vibrational stresses, it nevertheless adds very appreciably to the weight of the motor considered at a whole.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What I claim is:

1. In an internal combustion engine, a plurality of banks of engine cylinders, a crank shaft, an over-head cam shaft for each cylinder bank, a large reduction gear driven off the crank shaft, cam shaft driving mechanism including shafts and bevel gearing driven by the crank shaft thru said large reduction gear, a propeller shaft, and a yielding driving connection between said large reduction gear and said propeller shaft, said yielding driving connection being so related to the cam shaft driving mechanism as to relieve the cam shafts and said cam shaft driving mechanism of all torsional vibrational stresses due to irregularities in the rotation of said propeller shaft.

2. In an internal combustion motor, a crank shaft, a cam shaft, a direct connection between said crank shaft and said cam shaft including a reduction gear, a propeller shaft, and a yielding driving connection between said reduction gear and said propeller shaft.

In testimony whereof I hereunto affix my signature.

WILLIAM O. WARNER.
